RAIL ANCHOR

Edmund A. Skowron, Pittsburgh, and Wilbert H. Woodings, Oakmont, Pa., assignors to Woodings-Verona Tool Works, Verona, Pa., a corporation of Pennsylvania

Application June 8, 1944, Serial No. 539,241

2 Claims. (Cl. 238—330)

1

This invention relates to rail anchors, and more particularly to one-piece anchors that clamp onto rail bases.

In Woodings Patent No. 1,646,780 a one-piece resilient rail anchor is shown which is provided at one end with a jaw that hooks over one side of the rail base. The other end of the anchor extends upwardly and is provided in its lower portion with a notch for receiving the adjacent side of the rail base. In applying that anchor to a rail, it is placed under the rail with the jaw hooked over the rail base and with the upper part of the inner surface of its opposite end engaging the lower edge of the base at that side. A tool is applied to the anchor to swing it about its jaw and cause its up-turned end to slide upwardly across the side of the rail base until the notch snaps over the base to lock the anchor in position. That anchor has met with a great deal of success and is extensively used, but due to the shape of the convex inner surface of the up-turned end, considerable strength is required to force the hump up over the side of the rail. This tires the man who applies the anchors, and results in fewer anchors being applied to the rails per day than should be.

It is among the objects of this invention to provide a one-piece resilient rail anchor of the general character just referred to which can be applied to rails much more easily than those known heretofore, and, more specifically, which gradually opens at a substantially uniform rate as its up-turned end is moved up across the adjacent side of the rail base.

In accordance with this invention the anchor, which is adapted to extend under a rail base, has its opposite ends extending upwardly and close enough together that they must be sprung apart in order to receive the rail base between them. One end of the anchor is formed for gripping one side of the rail base while the anchor is moved into position by turning it about that end in order to force the upwardly extending opposite end of the anchor upwardly across the other side of the base. This last-mentioned end of the anchor has an inner surface that is concave lengthwise and which, when the anchor is being applied to the rail, slides upwardly across the lower edge of the adjacent side of the rail base and acts like a cam to spread the ends of the anchor apart. The lower end of this cam surface terminates at the upper end of a notch, with which the anchor is provided, for receiving the side of the rail base when the anchor is in position thereon. The gist of this invention is that the contour of the cam

2

surface is such that for each degree that the anchor is rotated to move the cam surface upwardly across the lower rail base edge, the anchor opens a substantially uniform amount until its ends are spread far enough apart to permit it to snap onto the rail base.

The preferred embodiment of the invention is illustrated in the accompanying drawing in which Fig. 1 shows our anchor hooked onto a rail base ready to be swung upwardly into final position, with the final position of the up-turned end shown in broken lines; and Fig. 2 is a fragmentary view showing the anchor jaw in final position on the rail.

Referring to the drawing, the anchor is made from a rectangular metal bar that is bent into the proper shape, such as that shown. The anchor preferably includes a central spring loop 1 extending downwardly and the upper ends of which are curved outwardly and downwardly to form surfaces 2 that bear against the bottom of a rail base 3. The opposite ends of the anchor extend upwardly, and the upper part of one of them is bent inwardly to form a jaw 4 for receiving one side of the rail base. The inside of this jaw has a substantially vertical inner wall adapted to lie flat against the side wall of the rail base, and an upper wall that inclines upwardly for the major portion of its length at substantially the same angle as the upper surface of the rail base. The rest of the upper wall extends upwardly at a much sharper angle to aid in applying the anchor to the rail. The inner lower wall 6 of the jaw is spaced from the bottom of the rail when the anchor is in position thereon, as shown in Fig. 2, and permits the anchor to be applied to the rail without spreading open the jaw.

The anchor's end 7 opposite the jaw extends upwardly a considerable distance, and its lower portion is provided with a notch 8 that receives the side of the rail base when the anchor is mounted on the rail with the up-turned end projecting above it. Due to the opposite ends of the anchor normally being closer together than the opposite sides of the rail base, the inner face 9 of the up-turned end above the notch serves as a cam surface which, in cooperation with the lower edge of the rail base that it engages during application of the anchor, spreads the ends of the anchor apart as the cam surface is forced upwardly on the rail.

It is a feature of this invention that cam surface 9 is so shaped that, as it slides upwardly across the lower rail base edge, the anchor opens gradually at a substantially uniform rate until

the ends are spread far enough apart to receive the rail base between them with one side projecting into notch 8. Accordingly, cam surface 9 is concave lengthwise with its lower end closer than any other part of that surface to the opposite end of the anchor. Furthermore, the curvature of the surface is such that it extends through the vertically spaced ends of a plurality of imaginary straight lines that converge at a point on the inner wall of the jaw engageable with the upper edge of the opposite side of the rail base. This point may be at the inner upper corner of the jaw even though the first point of engagement with the upper edge of the rail base is slightly lower, because the distance between these two points is too small to make any difference. These converging lines are uniformly spaced apart, and the length of each one is substantially uniformly greater than the one directly below it.

In laying out the contour of the cam surface, the following procedure may be followed. The location of the point of initial contact between cam surface 9 and the lower edge of the rail base is first decided upon. It is then easy to determine how far that point must move outwardly before the notch can snap into position on the rail base. Lines are then drawn from the initial contact point and from the most inwardly disposed point at the lower end of the cam surface to the upper inside corner of jaw 4. The angle formed between these two lines is then subdivided into degrees by a number of additional lines. The previously determined distance that the anchor must open is then divided by the number of spaces between all of these lines to find out how far the anchor should open for each degree of upward movement of the cam surface across the lower edge of the rail base. Starting at the lowest line, each successive line is then made longer than the one below it by an amount equal to the distance that the anchor is to open for each degree of upward rotation. A line drawn through the spaced ends of these degree lines will represent the curvature that the cam surface of the anchor should have.

A rail anchor constructed in accordance with this invention can be applied to a rail much more easily than previous anchors of this type, because the force required for that purpose is increased gradually and substantially uniformly and becomes greatest when the lower end of the cam surface reaches the rail, instead of quickly approaching its maximum close to the point of initial contact between cam surface and rail. This means that less physical effort is expended in applying these anchors to rails, so a greater quantity of them can be applied per day than heretofore.

According to the provisions of the patent statutes, we have explained the principle and construction of our invention and have illus-

trated and described what we now consider to represent its best embodiment. However, we desire to have it understood that, within the scope of the appended claims, the invention may be practiced otherwise than as specifically illustrated and described.

We claim:

1. A one-piece resilient rail anchor adapted to extend under a rail base, the opposite ends of the anchor extending upwardly and requiring to be sprung apart to receive the rail base between them, one end of the anchor being formed to hook over one side of the rail base and to engage its upper edge while the anchor is positioned by turning it about said upper edge to force the upwardly extending opposite end of the anchor upwardly and outwardly across the other side of the base, said opposite end of the anchor having an inner cam surface adapted to slide upwardly across the lower edge of the adjacent side of the rail base, the lower end of said surface terminating at the upper end of a notch with which the anchor is provided for receiving said adjacent side of the rail base when the anchor is in position thereon, and said cam surface being concave lengthwise and intersecting the vertically spaced ends of a plurality of imaginary straight lines converging at a point on the anchor engagable with the upper edge of the opposite side of the rail base, said lines being substantially one degree apart and the length of each one being substantially uniformly greater than the line directly below it.
2. A one-piece resilient rail anchor adapted to extend under a rail base and having a central depending loop portion the upper ends of which are adapted to bear tightly against the bottom of the rail, the opposite ends of the anchor extending upwardly and requiring to be sprung apart to receive the rail base between them, one end of the anchor being formed to hook over one side of the rail base and to engage its upper edge while the anchor is positioned by turning it about said upper edge to force the upwardly extending opposite end of the anchor upwardly and outwardly across the other side of the base, said opposite end of the anchor having an inner cam surface adapted to slide upwardly across the lower edge of the adjacent side of the rail base, the lower end of said surface terminating at the upper end of a notch with which the anchor is provided for receiving said adjacent side of the rail base when the anchor is in position thereon, and said cam surface being concave lengthwise and of such curvature that the anchor gradually opens at a substantially uniform rate as said cam surface is moved up across said rail base edge.
